(57) **CLAIM**

The ornamental design for a “cover suitable for use on a stroller or in a car,” as shown and described.

DESCRIPTION

FIG. 1 is a front view of the cover suitable for use on a stroller or in a car use according to the present invention; FIG. 2 is a front view thereof, showing a mesh window with cover turned back;

FIG. 3 is a front perspective view of the cover suitable for use on a stroller or in a car attached to a stroller with two front wheels;

FIG. 4 is a partial enlarged top front view thereof; and, FIG. 5 is a bottom front perspective view of the cover suitable for use on a stroller or in a car attached to a stroller with one front wheel.

The broken lines showing are for the purpose of illustrating environmental structures and form no part of the claimed design.

The broken lines shown on the cover suitable for use on a stroller or in a car illustrate stitching and form no part of the claimed design.

1 Claim, 4 Drawing Sheets
